WEFT INSERTING APPARATUS FOR LOOMS
WITH FIXED WEFT BOBBINS

Raymond Dewas, Amiens, France

Application February 3, 1933, Serial No. 655,021
In Germany February 19, 1932

1 Claim. (Cl. 139—126)

The present invention relates to weaving looms with continuous feed by means of fixed weft bobbins.

It has for its object a device for inserting the weft as single threads more particularly applicable to vertical looms and is characterized by:

A weft feeder or pinnless shuttle having a body of bifurcated form between the prongs of which there is a spring clip shaped like a hairpin, the springy prongs of which are arranged in the same direction as the prongs of the bifurcated member, are in contact with one another for a great part of their length and are bent over towards the outside at their ends so as to facilitate the introduction of the end of the weft thread which must be passed through the shed.

A member intended to present to the weft feeder, at the moment when it enters the shed, the taut weft at the entrance of the said shed, the said member consisting of a clip which may have the same shape as that of the weft feeder and which is mounted, either on the sley or in some other suitable manner.

A member which has for its object the freeing of the end of the weft from the weft feeder after the passing of the thread.

In order to explain the invention, and by way of an example of application, the latter is described and illustrated hereinafter, applied by way of an example to a vertical loom in which the parts of the loom, generally, are arranged vertically, the threads of the warp and the shed being vertical, the weft feeder passing vertically from top to bottom through the vertical shed, and the return movement of the weft feeder and its subsequent throw being ensured by suitable transporters and distributors of an already known design.

In the drawing:

Figure 1 is a perspective view in elevation of the weft feeder.

Figure 1a is a section along the line a—a of Fig. 1.

Figure 2 is a detail view showing the spring clip which holds the weft and which is arranged in the inside of the weft feeder between the prongs.

Figure 3 is a side elevation of a vertical loom, a single weft thread having been passed through and beaten up, the said weft being caught by the clip on the sley.

Figure 4 is a similar view, the shed having been formed and the weft stretched at the entrance of the shed in the path of the weft feeder

in order to be gripped and carried along by the latter through the shed.

Figure 5 is a plan view of Figure 4 seen from above.

Figure 6 is a side elevation of the guide.

Figure 7 is a section through the guide along the line 7—7 of Fig. 6.

The weft feed consists principally of a weft carrier 1, preferably of metal, of bifurcated form having two prongs 2 on account of its being divided for the greater part of its height by a centrally disposed slot 3. In this slot and disposed in seats 2a and 2b (Fig. 1a) arranged on the interior faces of the slot is placed the spring clip 4 which consists of a flat band bent into the shape of a hairpin (Fig. 2), the prongs 5 of which are arranged in the same direction as the prongs of the bifurcated part, in springy contact with each other and at their ends 5' bent outward so as to facilitate the insertion of the end of the weft thread which is to be introduced into the shed.

The clip 4 is held in the slot 3 of the weft-carrier 1 by its ends 5' situated within the seats 2b and by its round portion situated within the seat 2a (Fig. 1a).

The different members of the loom are arranged vertically and are as follows: 6 is the warp beam, 7 are the threads of the warp divided into two groups of threads 7a and 7b when they form the shed 8, and 9 is the cloth roller.

10 is the sley and 11 are the healds.

12 is a spring clip which seizes hold and presents the weft to the feeder. This clip is similar to the clip 4 of the body part 1 and is arranged in any desired way at the end of the sley 10, holding the end of the weft 13, stretched between it and the feed bobbin 14, passing through the eyelet 15' which is arranged at the end of the guide piece 15 of the distributor for the weft feeder 1, the tension of the weft 13 being ensured automatically by a mobile tensioning rod 16 which takes up the slack of the weft which is required by the play of the sley when the weft is beaten up.

Owing to this device for inserting the weft, when the end 13' of the weft thread 13 is held in the spring clip 12 and the sley 10 has moved back towards the healds 11 (Figure 1) the weft 13 is stretched across the shed 8 (Figure 5).

The weft feeder 1 on leaving the guide piece 15 will be disposed astride the thread 13 which is stretched, gripping it between its prongs 5 which form part of the clip 4. The thread is easily engaged between the ends 5' of the clip 4 due to the shape thereof. When the thread 13

is moved, its resistance will partly balance that exerted by the clip 12 on the end 13'; the thread 13 will be moved further towards the round portion of the clip 4 and will be held more and more 5 tightly by the prongs 5, until the gripping force of the prongs 5 will be stronger than the force exerted by the clip 12 on the end 13'. This will cause the pulling of the end 13' of the weft thread 13 out of the springy clip 12 of the sley 10. 10 When the weft feeder 1 has traversed the shed the sley 10 will beat up the weft which has been passed and the clip 12 will seize, at the point of weaving of the piece of stuff 17 (Fig. 3), the weft which comes from the bobbin and which is 15 guided over a small cutting blade 18 which severs it between the said point 17 and the said clip 12, the end of the cut thread 13' thus remaining held in the clip whilst the sley moves backwards and the movable tensioning rod 16 maintains the tension of the weft 13 between the clip and the bobbin. 20

Figures 6 and 7 illustrate the cooperation of the weft carrier 1 with the guide 15. As shown in these figures, the guide 15 has the form of a hollow rectangular tube. The weft carrier 1 is caused to move within this tube by any suitable means of the generally known type. 25

The weft is inserted from only one side of the loom, namely, from top to bottom by the weft-carrier 1 which is either thrown or falls by gravity 30 from the guide piece 15; the weft-carrier 1 grasps the weft thread stretched across the shed 8 above the upper threads of the warp 1a and 1b and between the eyelet 15' and the clip 12, and then 35 passes through said shed.

After the weft-carrier 1 carrying the weft-thread has passed through the shed 8, the sley 10 beats this thread against the preceding thread 40 of the fell 17 of the cloth.

The thread pressed against the fell is held in the usual manner by the change of the shed which traverses the divided threads of the warp.

The weft-carrier, after having passed through the shed 8 is stopped and pushed into a guiding member or groove bringing it to a conveyer which transports it to the guide piece 15. From there, it is again thrown through another shed, since obviously there are many weft-carriers which are thrown successively one after another through 10 successive sheds.

The end 13' of the weft-thread is disengaged from the prongs 5 of the clip 4 at the time when the weft-carrier is pushed into the groove towards the conveyor. The end 13' of the weft-thread is 15 caused to slide along the prongs 5 until it leaves these prongs by the tractive force exerted by the weft-carrier which is moving in the groove.

It is also possible to provide a finger attached to the inner portion of the sley 10 which pushes 20 the thread stretched between the inner extremity of the cloth and the weft-carrier after the latter has passed through the shed 8. This finger pulls the thread out of the prongs 5 of the clip 4. 25

I claim:

A device for inserting the weft as single threads by a pinnless shuttle or weft feeder for weaving looms having fixed weft bobbins, more particularly for vertical looms, said device comprising a weft feeder of bifurcated form, said weft feeder comprising a pair of prongs; and an elastic clip having the shape of a hairpin and situated between the prongs of said weft feeder, said clip comprising a pair of elastic prongs; the prongs of said clip extending in the same direction as the prongs 30 of said weft feeder and being in contact with the prongs of said weft feeder, the ends of the prongs of said clip being bent outwardly to facilitate the insertion of the weft-thread. 35
